WITNESS:

ATTORNEY

UNITED STATES PATENT OFFICE.

HENRY B. JENNINGS, JR., OF LONG ISLAND, VIRGINIA.

LOOSE-LEAF BINDER.

Application filed June 18, 1924. Serial No. 720,822.

This invention relates to improvements in loose leaf binders and has for an object the provision of a binder unit which includes a main binder and an auxiliary binder so connected as to provide a loose leaf book, including a reference book and a loose leaf note book, the invention being especially useful for Bibles of ministers.

Another object of the invention is the provision of a binder which may be arranged in book form and in which the leaves will lie perfectly flat when the book is open, so that notations thereon may be readily accessible and additional notes conveniently added.

Another object of the invention is the provision of a loose leaf binder which is simple in construction and may be readily manipulated for the insertion and removal of leaves.

With the above and other objects in view, the invention further includes the following novel features and details of construction, to be hereinafter more fully described, illustrated in the accompanying drawings and pointed out in the appended claims.

In the drawings:

Figure 1 is a plan view of a book which includes a loose leaf binder constructed in accordance with the invention, the book being shown open.

Figure 2 is a fragmentary end view on an enlarged scale with the parts in the position shown in Figure 1.

Figure 3 is a view similar to Figure 2 but showing one edge of the back of the book released so that the leaves will lie perfectly flat.

Figure 4 is an enlarged fragmentary sectional view with the parts in the position shown in Figure 2.

Figure 5 is a sectional view with the parts in the position shown in Figure 3.

Figure 6 is a plan view partly broken away and showing the parts in the position illustrated in Figure 5.

Figure 7 is a sectional view on the line 7—7 of Figure 4.

Figure 8 is an enlarged fragmentary sectional view showing the means for locking the hooks of the auxiliary binder.

Figure 9 is a fragmentary plan view of a portion of the spring actuated locking rod and its guide.

Figure 10 is a detail perspective view of the bail.

Figure 11 is a fragmentary sectional view taken substantially on the line 11—11 of Figure 6.

Referring to the drawings in detail where-in like characters of reference denote corresponding parts, the invention is shown in connection with a combination text and note book, the text book being indicated at 10 and the note book at 11. It is of course obvious that the book may be of any character, but the invention is designed especially for use with a Bible, the cover of which is shown at 12, the said cover serving to enclose both the book 10 and the book 11.

The Bible or book 10 has its leaves removable held in place by what may be termed the main binder or main clamp 13. This main clamp is substantially U-shaped and includes a transversely L-shaped member and a removable plate, the latter being shown at 14. This plate is detachably secured to the L-shaped member and together with said member provides a transversely channel-shaped clamp, the parts of which are connected by two studs 15 which are spaced along the clamp. These studs are provided at one end with heads 16 which are received within openings 17 provided in the L-shaped member of the clamp, while the shanks of the studs extend through a removable clamping plate 18. The opposite ends of the studs 15 are provided with threaded sockets for the reception of studs 15' by means of which the members of the clamp 13 are held in associated relation. The main binder or clamp 13 carries at each end substantially rectangular end plates 20 whose area is greater than the transverse area of the clamp 13 so as to extend beyond the sides of the said clamp.

The L-shaped member of the clamp 13 is arranged to provide a guide groove or channel 21, the latter being preferably formed by securing an inverted channel bar 21' upon the L-shaped member so as to provide spaced plates, while between these plates there is located a longitudinally slidable locking bar 22. This bar 22 is adapted for engagement with two of the hooks 23 which are spaced along the binder, these hooks together with the slide 22 and a portion of the L-shaped member 13 of the main clamp, forming a part of an auxiliary binder or clamp within which are secured the leaves of the note book 11. The hooks 23 are as shown in Figures 6 and 7, arranged in pairs and extend upward from a bar 24 which extends

along the back of the main clamp 13 and whose opposite ends are provided with reduced extensions or lugs 25. These extensions or lugs 25 extend through and are slideable vertically within slots 26 provided in the end plates 20 so that the hooks may be moved inward and outward with respect to the binder. One of the ends of the hooks are secured to the bar 24 while their opposite ends are notched as shown at 27, while the locking bar 22 is provided with spaced key-hole slots 28 which receive these notched ends of the hooks 23 and which when moved longitudinally will cause one edge of the 15 key-hole slots to enter and engage the walls of the notches 27 and hold the hooks in locked position. To permit the ends of the hooks 23 to enter the notches 27, the member 13 is provided with openings 13' beneath these notches as shown in Figure 8 of the drawings. This is clearly illustrated in Figure 8 of the drawings. The hooks 23 may be thus manipulated and the leaves of the note book 11 removed or inserted without disturbing the leaves of the book 10.

The plate 18 and the channel bar 21' are removably secured to the L-shaped member 13 by means of studs 15' so that by removing these studs the channel-shaped member may be detached while the leaves of the book 10 may be removed through the removal of the screws 19 and the member 14 of the main clamp.

By reference to Figure 7 it will be seen that the studs 15' are located at opposite ends, or at the top and bottom ends of the book, while the studs 15 are located intermediately. The studs 15, as before stated, have their heads bearing upon the plate 18, while studs 15' extend upward and are provided with beveled heads 29' which engage the walls of beveled openings provided in the channel bar 21' as seen in Figure 6 of the drawings. By reference to this figure it will be noted that the locking bar 22 terminates sufficiently short of the ends of the member 13 and the bar 21' to permit of this construction. The studs 15', which are secured in place by the screws 29, are slightly longer than the studs 15 which are secured by the studs 15.

The locking bar 22 has extending from one edge an operating lug 22^a which operates within a notch 22^b provided in the channel bar 21', the shoulders at the opposite ends of this notch forming stops to limit sliding movement of the locking bar 22 in either direction.

Pivoted secured between the end plates 20 as shown at 30 is a plate 31, the latter being secured to the back of the book cover by means of a clamping plate 32 having in-turned ends. This clamping plate 32 acts to clamp between it and the plate 31, a flexible strip 33 which has its opposite ends secured

to the book cover 12. If desired this strip 33 may be in the form of a sheet or lining for the cover 12. The opposite edge of the plate 31 has pivotally secured thereto as shown at 34, a locking plate 35 whose free rolled edge 36 is adapted to be clamped upon the leaves 11 as shown in Figure 4 of the drawings. This locking plate 35 is provided underneath with spaced guides 37 within which is slidingly mounted a locking rod 38, said rod extending beyond the ends of the locking plate. This rod is adapted to enter notches 39 provided in the end plates 20 and when so engaged will hold the plate 35 in the position shown in Figure 4. The locking rod 38 is provided at one end with a right-angularly disposed loop or finger piece 38' by means of which the rod may be moved longitudinally. This longitudinal movement will disengage the opposite end of the rod 38 from its notch 39 in one of the end plates 20, while in order to disengage the end of the rod 38 adjacent the finger piece, this end of the rod is flexed or moved laterally. A spring 40 which is secured to one of the spaced guides 37 has one of its ends engaged with the rod 38 as shown in Figure 9 of the drawings and this spring acts to yieldingly resist longitudinal movement of the rod and holds the latter in engaged position.

The slide bar 24 which carries the hooks 23 is formed of a transversely substantially J-shaped bar, the lower edge of which provides a groove to receive the wire connecting portion between the hooks 23 of each pair, while spaced bearings 24' are rigid with the bar 24 and receive the adjacent end portions of the hooks.

By means of the construction just described it will be apparent that one edge of the back of the cover 12 of the book may be unfolded as shown in Figures 3 and 5 so that the leaves of the note book 11 may be opened so as to lie absolutely flat. In order to provide a rest for the opened leaves the space between the released edge of the back of the book cover and the upper edge of the binder is bridged by the locking plate 35 and in order to hold the locking plate in this position and to facilitate the releasing and locking of the plate 35 there is provided a bail 41 which is pivoted within the rolled edge 36 of the plate 35 and whose opposite ends are pivotally mounted at 41' within the end plates 20 so that when the book is arranged as shown in Figure 5 the leaves of the note book 11 may be opened to the left in the said figure to lie upon the locking plate.

The swinging movement of the bail 41 may be seen by reference to Figures 2, 3, 4 and 5 of the drawings. In Figures 2 and 4 the clamping plate 32 is in position to lock the note book 11 in place. By releasing the

locking bar 38 in the manner previously described, the rolled edge 36 of the plate 35 may be swung upward and outward, or to the left of the drawings. This is possible 5 due to the pivotal mounting of the inturned ends of the bail 41 in the end plates 20. This upward and outward movement will cause the bail to move over the upper ends 10 of the end plates 20 until it reaches the position illustrated in Figures 3 and 5 of the drawings.

The invention is susceptible of various changes in its form, proportions and minor details of construction and the right is here- 15 in reserved to make such changes as properly fall within the scope of the appended claims.

Having described the invention what is claimed is:—

1. In a loose leaf binder, a sectional trans- 20 versely channel-shaped clamp, means extending transversely of the clamp for removably securing the sections together, and means for engagement with leaves, a cover, means connecting the back of the cover with 25 the clamp including means whereby one edge of the back may be released.

2. In a loose leaf binder, a sectional trans- 30 versely channel-shaped clamp, means for removably securing the sections together, means extending transversely of the clamp for engagement with leaves, a cover, a back 35 plate having one edge hingedly secured to one edge of the clamp, means connecting the cover to the back of the plate, a locking plate hingedly connected with the back plate, whereby said plate may be swung laterally with relation to the clamp, and means for locking the plate with relation to the clamp.

3. In a loose leaf binder, a main binder 40 including a transversely channel-shaped leaf-receiving clamp, an auxiliary binder mounted thereon, said auxiliary binder including leaf-engaging hooks, means connect- 45 ing together one end of all of the hooks, means for mounting the hook-connecting means upon the main binder for relative vertical movement whereby the hooks may be engaged with or disengaged from the 50 leaves and means for locking the opposite ends of the hooks to the main binder.

4. In a loose leaf binder, a main binder including a transversely channel-shaped leaf-receiving clamp, an auxiliary binder

mounted thereon, said binder including 55 vertically movable leaf-engaging hooks, means connecting the hooks to provide for simultaneous movement whereby said hooks may be engaged with or disengaged from the leaves and means for locking the hooks 60 against accidental movement.

5. In a loose leaf binder, a main binder including a transversely channel-shaped leaf-receiving clamp, an auxiliary binder mounted thereon, said auxiliary binder in- 65 cluding leaf-engaging hooks, means connect- 70 ing together one end of all of the hooks, means for mounting the hook-connecting means upon the main binder for relative vertical movement whereby the hooks may be engaged with or disengaged from the 75 leaves and a longitudinally movable locking bar detachably engaging the opposite ends of the hooks.

6. In a loose leaf binder, a main binder 75 including a transversely channel-shaped leaf-receiving clamp, an auxiliary binder mounted thereon, said auxiliary binder in- 80 cluding leaf-engaging hooks, means connect- 85 ing together one end of all of the hooks, means for mounting the hook-connecting means upon the main binder for relative vertical movement whereby the hooks may be engaged with or disengaged from the leaves and means carried by the main binder 85 and detachably engaging the hooks for lock- 90 ing the same against accidental movement.

7. In a loose leaf binder, a main binder means including a transversely channel- 90 shaped leaf-receiving clamp, a locking bar 95 mounted for longitudinal sliding movement upon the main binder, an auxiliary binder mounted upon the main binder, comprising leaf-engaging hooks for the auxiliary binder and means at one end of the hooks for de- 95 tachable engagement with the locking bar.

8. In a loose leaf binder, a main binder for the retention of substantially permanent leaves, means supported upon the main binder for the retention of temporary leaves 100 in a position to overlie and substantially register with the substantially permanent leaves, and means supported by the main binder for clamping said temporary leaves 105 in overlying position when the binder is 105 completely closed.

In testimony whereof I affix my signature.
HENRY B. JENNINGS, JR.
